CARBURETOR

Grant Hammond, New Haven, Conn.

Application January 8, 1930. Serial No. 419,242

18 Claims. (Cl. 261—50)

My invention relates to the class of devices that are employed for the purpose of mixing fluids, more especially for combustion purposes, and an object of my invention, among others, is the production of a device of this class that shall be extremely efficient for the purpose for which it is employed.

One form of a carburetor embodying my invention and in the construction and use of which the objects herein set out, as well as others, may be attained, is illustrated in the accompanying drawing, in which—

Figure 1 is a view in central lengthwise section through my improved carburetor showing the valves closed.

Figure 2 is a side view of the same.

Figure 3 is a view in cross section on a plane denoted by the dotted line 3—3 of Figure 1.

Figure 4 is a detail view illustrating the construction and operation of the throttle cam and on a plane denoted by the dotted line 4—4 of Figure 1.

Figure 5 is an isometric view of the outer end of the throttle lever and its connected actuator.

In the accompanying drawing the numeral 5 indicates the shell of my improved carburetor that may be provided in its interior with a venturi 6. This shell is preferably round in cross section and it has a flange 7 as a means for attaching the shell to a support therefor. A shallow groove 8 is formed in one side of the shell, extending lengthwise thereof and a valve support 9 is seated in this groove for sliding movement therein.

A housing 10 is fitted in said groove, being seated at one end against a spacer 11 and being held in place at this end by a screw passing through the upper end of the housing and spacer, and also through a plate 12 secured tightly against the outer surface of the shell as by means of screws and firmly holding the housing in position. A chamber 13 is formed within the support 9 and as shown in Figures 1 and 2 of the drawing, in which chamber the support 9 freely slides.

A wearing plate 14, preferably of hard, tough metal, is secured in a recess in the support 9, this plate having a hole 15 of peculiar shape to be hereinafter described, and in which hole a throttle crank pin 16 projects from the end of a throttle shaft 17 mounted in a hub in the plate 12 and having a throttle lever 18 secured to its outer end.

The housing 10 has a supporting foot 19 projecting from its end across the end of the shell

5, and as shown in Figure 1 of the drawing, said foot having a threaded recess to receive the lower end of a fuel inlet tube 20 to which combustible fluid is supplied as through a threaded nipple 21 connected in any desired manner with a source of fluid supply.

A needle valve 22 is seated against a valve closing spring 23 located in the tube 20, said spring resting upon the inner end of a screw threaded stud in the foot 19. The needle valve has lengthwise grooves 24 for flow of liquid fuel along the tube 20, the tapered inner end of said needle valve projecting through an outlet port in the inner end of said tube 20, and as shown in Figure 1.

The tube 20 projects lengthwise within an idling air supply tube 25, extending inwardly from one end of the shell 5 and supported by an adjusting nut 26 through which said air tube projects and within which it loosely fits for sliding movement therein, said nut being attached by interengaging screw threads to a main air or throttle valve 27 seated squarely against the end of the shell 5 which forms a valve seat therefor, said valve being rigidly secured to one end of the valve support 9. The edge of this valve and the edge of the shell are oppositely beveled to reduce to a minimum the contacting surface between the valve seat and valve as shown in Figures 1 and 2.

From this it will be seen that the main air or throttle valve is moved bodily away from the end 85 of the shell against which it is seated and air is admitted equally to the shell around all sides of the valve, this movement being effected through the operation of the sliding support 9 that is actuated through the medium of the throttle lever 18.

A valve actuating bar 28 extends across the end of the tube 25 in contact with the end of the needle valve, and when the throttle valve 27 is operated to admit air it effects movement of the tube 25 thereby actuating the needle valve to admit fluid within 95 the shell 5. By turning the nut 26 in the valve 27 the position of the tube 25 and bar 28 are changed, thereby adjusting the needle valve 22 for supply of fuel for idling purposes of the engine.

Air inlet holes 29 are formed through the side 100 of the tube 25 at its lower end and a valve 30 in the form of a flanged nut is screw threadedly engaged with the end of said tube 25, the flange on the valve being located opposite the holes 29, and by turning the valve 30, the sizes of the holes may 105 be regulated for admission of the proper amount of air for idling operation of the engine.

There is a material advantage in causing the throttle valve to leave its seat on the end of the shell 5 simultaneously at all points around the 110

edge of the shell, the air being thereby admitted in substantially equal amounts on all sides whereby a most thorough mixing of the air and combustion fluid takes place.

5 When the valve is seated quite a little more force is required to unseat it than is required to afterwards effect its movement, and I have therefore provided means to effect a very slow movement of the valve away from its seat as compared 10 with the rate of movement of the throttle actuator, and to gradually accelerate this movement in proportion to the distance traveled by the valve away from its seat. A part of this mechanism embodies an unseating member comprising the pin 16 and its cam connection with the support 9. In 15 this arrangement herein shown the point of contact between the crank pin 16 and the slide 9 when the throttle valve is closed is substantially in the axial line of the slide 9, that is, a line drawn 20 centrally through the slide lengthwise thereof, and the pin is in contact with an edge of the hole 15 extending substantially at right angles to said axial line said edge at its inner end extending slightly away from the pin and as shown in Figure 25 4. A nose 31 is extended from the pin 16 and this nose may be relieved on that side adjacent to the edge of the hole 15.

Another part of the mechanism includes an 30 accelerating member for accelerating valve movement is embodied in the shape of the throttle lever 18 and in its connection with a throttle actuating rod 32 extending from the throttle lever and connected in any suitable manner with the means for manually operating the throttle 35 mechanism. The edge 33 is especially curved to contact with a shoe 34 secured between the branches of the forked end of the rod 32, said shoe also being slightly curved as shown in Figure 40 2 of the drawing. The radius of the curve of the edge 33 of the throttle lever is gradually decreased, becoming very abrupt at the inner end where it terminates in a notch 35 into which the 45 end of the shoe 34 sinks toward or at the end of the opening movement of the throttle or main air valve 27.

From this it will be seen that the degree of rotation of the throttle shaft 17 is comparatively slight as compared with the amount of movement 50 of the throttle actuating rod 32 and the outer end of the lever 18, and hence the effect communicated to the throttle valve 27 is to produce a very slight movement of said valve as compared with the amount of movement of the 55 actuating rod 32, and this slowness of opening movement of the throttle valve 27 is accentuated and further materially lessened by the arrangement of the crank pin 16 and hole 15 engaged thereby in which the degree of movement of the lever 18 as compared with the amount of movement 60 of the slide 10, and hence the throttle valve, will be comparatively great, but as the valve is unseated sufficiently to overcome the force holding it to its seat, the nose 31 takes action against the straight edge of the hole 15 with a result 65 that the opening movement of the valve will be accelerated without increased rate of movement of the lever, this acceleration being gradual but at the same time quite rapid, and the valve will therefore be given a comparatively rapid movement 70 after it is thoroughly unseated. The effect of this construction of the lever 18 and pin 16 is to apply a maximum amount of leverage to the valve at the beginning of opening movement thereof and to gradually lessen such leverage 75 during such opening movement.

The throttle lever extends through between the branches of the forked end of the rod 32, and said branches pass through notches in opposite ends of the hub 36 of said lever 18. A spring 80 pressed plunger 37 extends out of a hole in the rod 32 and is pressed against the edge of the lever 18, and as shown in dotted lines in Figure 2, this plunger with its spring affording a yielding connection between the rod 32 and the lever 18 and the spring acting to swing the lever 18 to and 85 maintain it in its closed position as shown in Figure 2.

It is often desirable to suddenly enrich the mixture by increasing the amount of combustible fluid in proportion to the amount of air, in order 90 to enable the engine with which the carburetor is connected to perform extra heavy duty. This is particularly the case when the carburetor is used in connection with an automobile engine, as when suddenly encountering mud or mire, 95 or a heavy grade or other conditions requiring added power. It is also essential that this operation of enriching the mixture shall take place with a minimum degree of effort on the part of the operator. It have provided means wherein 100 this result may be attained simply by an increased movement of the manually actuated mechanism for operating the throttle valve. I accomplish this by suddenly reducing the end 105 38 of the needle valve at such distance from the mouth of the inlet tube 20 as will not be required for use except under conditions requiring increased power. Under ordinary conditions of running, as on down-grades, level stretches, or slight up-grades, that portion of the needle valve 110 up to the shoulder defining the reduced end 38 will be sufficient to maintain any speed for which the vehicle is designed. When the requirement for extra power suddenly takes place, all that is needed is to give added movement to the throttle 115 mechanism so that the reduced end 38 of the valve will be drawn into the mouth of the opening in the tube 20, thereby suddenly enriching the mixture.

For priming purposes, as for starting operations, I may employ a priming rod 39 having one end engaged with the flange of the valve 30 and its opposite end engaged with a priming lever 40 pivotally mounted on the foot 19 and arranged to be connected with any suitable manually operated priming device in a manner that will be readily understood. By operating the lever 40, it will be noted that the air supply tube 25 is pulled outwardly thereby causing the bar 28 to open the needle valve, and this without affecting 130 the air inlets.

In accordance with the provisions of the patent statutes I have described the principles of operation of my invention, together with the device which I now consider to represent the best 135 embodiment thereof; but I desire to have it understood that the device shown is only illustrative, and that the invention may be carried out by other means and applied to uses other than those above set out.

I claim—

1. A carburetor including a shell, a throttle valve for admitting air to said shell, a valve actuating member, and a connection between said valve and actuating member arranged to apply 145 a maximum amount of leverage at the beginning of opening movement of the valve and to gradually decrease said leverage during such opening movement by a constant movement of the accelerating member.

2. A carburetor including a shell, a throttle valve for admitting air to said shell, a valve operating member, and a connection between said valve and said operating member, said connection including a rotatably mounted pin and a member having a hole with a pin engaging edge, said pin having a nose extending to accelerate valve movement after unseating movement thereof. 5
- 10 3. A carburetor including a shell, a throttle valve for admitting air to said shell, a valve actuating member, and a connection between said valve and actuating member including a rotatably mounted pin engaged with the edge of a hole in a member of said connection, said pin having an extended nose to accelerate valve movement after the unseating movement thereof, and said nose being relieved on that side toward the edge to retard rate of opening movement of the valve. 15
- 15 4. A carburetor including a shell open at one end, a throttle valve seated against the end of said shell, a slide located in a groove in the outer side of said shell and rigidly secured to said valve, a slide housing secured to the side of the shell to cover said slide, a throttle shaft rotatably mounted in said housing and engaged with said slide, and a throttle lever secured to said shaft. 20
- 20 5. A carburetor including a shell open at one end, a throttle valve seated against the end of said shell, a slide located in a groove in the outer side of said shell and rigidly secured to said valve, a slide housing secured to the side of the shell to cover said slide and having a supporting foot extending opposite the end of said shell, carbureting mechanism supported by said foot, a throttle shaft rotatably mounted in said housing and engaged with said slide, and a throttle lever secured to said shaft. 25
- 25 6. A carburetor including a shell open at one end in line with its axis, a throttle valve seated upon the edge of said opening outside of the shell, means for operating said valve, an inlet for combustible fluid to the interior of the shell, a valve for said inlet with its end located within the shell, a valve actuating bar engaged with said end of said valve, and an operative connection between said bar and the valve seated against the edge of the opening in the end of the shell. 30
- 30 7. A carburetor including a shell open at one end, a throttle valve seated upon the edge of said opening, means for operating said valve, a fuel tube extending through said valve to supply a combustible fluid to the interior of the shell, a needle valve in said tube and projecting beyond its outer end, an air supply tube secured to the throttle valve and enclosing said fuel tube, and a bar extending across the mouth of said air supply tube to engage the end of said needle valve. 35
- 35 8. A carburetor including a shell open at one end, a throttle valve seated upon the edge of said opening, a slide movably mounted on the shell and rigidly connected with said valve, a housing having a supporting foot located opposite the opening into the shell, means for operating said slide, a fuel conducting tube secured to said foot and projecting into the shell, an air supply tube secured to the throttle valve and projecting into the shell surrounding the fuel conducting tube, a bar extending across the mouth of said air conducting tube, and a needle valve located in said fuel conducting tube and project- 40
- 40 ing beyond the mouth thereof in the path of movement of said bar. 45
- 45 9. A carburetor including a shell open at one end, a throttle valve seated upon the edge of said opening, means for operating said throttle valve, an adjusting nut screw threadedly engaged with the throttle valve, an air conducting tube secured to said nut and projecting into the shell, a fuel conducting tube projecting into said air conducting tube and connected with a source of fuel supply, a bar projecting across the mouth of said air supply tube, and a needle valve projecting out of the end of said fuel supply tube in the path of movement of said bar. 50
- 50 10. A carburetor including a shell open at one end, a throttle valve seated against the edge of the opening in said shell, means for operating said valve, an air conducting tube secured to the throttle valve and projecting into the shell, and having lateral openings in its outer end, a valve adjustably mounted on the end of said air conducting tube to regulate the size of said openings, and means for supplying fuel within said shell. 55
- 55 11. A carburetor including a shell open at one end, a throttle valve seated upon the edge of said opening, means for operating the throttle valve, a recessed nut adjustably secured to said throttle valve, an air conducting tube secured to said nut and projecting into said shell, said tube having lateral openings in its outer end, a valve nut screw threadedly engaged with the outer end of said air conducting tube and having a flange to govern the size of said openings, and means for introducing a combustible fluid into said air supply tube and for regulating the flow of said fluid. 60
- 60 12. A carburetor including a shell, a throttle valve to control flow of fluid into said shell, a throttle actuating member, a connection between said member and said valve and including a lever having a curved edge gradually decreasing in radius from its outer end inwardly and a member engaging said lever, and means for gradually changing the points of engagement of said lever and member during the operation of actuating said valve. 65
- 65 13. A carburetor including a shell, a throttle valve to control flow of fluid into said shell, a throttle actuating member, a connection between said member and said valve and including a pivotally mounted lever having a curved edge, and a shoe projecting from said member into contact with the curved edge of said lever. 70
- 70 14. A carburetor including a shell, a throttle valve to control flow of fluid into said shell, a throttle actuating member, a connection between said member and said valve and including a pivotally mounted lever, means to engage said lever and said member for sliding movement of said member relatively to said lever but to prevent lateral movement of said member relatively to said lever, and a shoe projecting from said member into contact with the edge of said lever. 75
- 75 15. A carburetor including a shell, a throttle valve to control flow of fluid into said shell, a throttle actuating member, a connection between said member and said valve and including a pivotally mounted lever having a hub with notches therein, a forked end on said member having its branches engaged in said notches, and a shoe projecting from said branched end into contact with said lever. 80
- 80 16. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 85
- 85 17. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 90
- 90 18. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 95
- 95 19. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 100
- 100 20. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 105
- 105 21. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 110
- 110 22. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 115
- 115 23. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 120
- 120 24. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 125
- 125 25. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 130
- 130 26. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 135
- 135 27. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 140
- 140 28. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 145
- 145 29. A carburetor including a shell, a throttle valve to control flow of fluid into said shell, a throttle actuating member, a connection between said member and said valve and including a pivotally mounted lever having a curved edge, and a shoe projecting from said member into contact with the edge of said lever. 150

totally mounted lever, means for connecting said member and said lever and including a shoe projecting from said member into contact with the edge of said lever, and means for holding said shoe in yielding contact with said lever.

17. A carburetor including a shell, a throttle valve to control flow of fluid into said shell, a throttle actuating member, a connection between said member and said valve and including means for increasing the amount of opening movement of said valve in proportion to the amount of movement of said member, and a supplemental mechanism for increasing the amount of open-

ing movement of said valve in proportion to the amount of movement of said member.

18. A carburetor including a shell, a throttle valve to control flow of fluid into said shell, a throttle actuating member, a connection between said member and said valve and including means for increasing the amount of opening movement of said valve in proportion to the amount of movement of said member, and a supplemental mechanism including a lever with means for decreasing the power of said lever during the opening movement of said valve.
